UNITED STATES PATENT OFFICE.

HARRY CLAYTON, OF PHILADELPHIA, PENNSYLVANIA.

FAN.

SPECIFICATION forming part of Letters Patent No. 225,346, dated March 9, 1880.

Application filed August 18, 1879.

To all whom it may concern:

Be it known that I, HARRY CLAYTON, of the city and county of Philadelphia, and State of Pennsylvania, have invented a new and useful Improvement in Fans, which improvement is fully set forth in the following specification and accompanying drawings, in which—

Figure 1 is a side elevation of the fan embodying my invention. Fig. 2 is a face view thereof.

Similar letters of reference indicate corresponding parts in the two figures.

My invention consists in swinging arms suspended from a ceiling, or elsewhere overhead, and firmly connected by a cross-piece, in combination with a swinging fan which is suspended from said arms, so as to be powerfully operated.

It also consists in crossing the swinging arms, whereby they are firmly connected.

Referring to the drawings, A represents two arms, which are suspended by means of hooks and eyes from the ceiling of an apartment, horizontal arms, or other suitable places overhead.

B represents a fan, consisting of a frame with suitable cloth or paper stretched thereon, or otherwise constructed, as now well known. This fan is suspended from the lower end of arms A by means of hooks and eyes or other hinged joints.

It will be seen that the fan has a free motion at its place of connection with the arms A, and said arms have a free motion at their places of connection with the ceiling. Conse-

quently, when the arms are swung or operated by means of the cord or connection C, the fan receives swinging motions independent of the swinging motions of the arms, and thus operates with great power, the air being violently agitated thereby.

The lower ends of the arms A are connected by a cross-piece, D, which may be weighted for evident purposes, and the cord or connection C may be provided with a handle and pass over pulleys for ease of operation.

The arms A are crossed at their centers or other suitable points, and there nailed, screwed, or otherwise fastened; and as they are connected below by the piece D, it is evident that they are firmly and securely attached and enabled to withstand the strain to which they are subjected.

Having thus described my invention, what I claim as new, and desire to secure by Letters Patent, is—

1. The suspended swinging arms A, provided with the connecting-piece D, the swinging fan B, suspended therefrom, and the operating cord or connection C, combined and arranged to operate substantially as and for the purpose set forth.

2. The swinging cross-arms A, with connecting-piece D, and the swinging fan B, combined and arranged to operate substantially as and for the purpose set forth.

HARRY CLAYTON.
